US0D1013282S

(12) **United States Design Patent** (10) **Patent No.:** **US D1,013,282 S**
(45) **Date of Patent:** **** Jan. 30, 2024**

(54) **EARMUFFS**

(71) Applicant: **Alpine Nederland B.V.**, Soesterberg (NL)

(72) Inventor: **Roderik Bos**, Zeist (NL)

(73) Assignee: **ALPINE NEDERLAND B.V.**, Soesterberg (NL)

(**) Term: **15 Years**

(21) Appl. No.: **29/786,788**

(22) Filed: **Jun. 2, 2021**

(30) **Foreign Application Priority Data**

Dec. 7, 2020 (EM) 008309215-0001

(51) **LOC (14) Cl.** **29-02**

(52) **U.S. Cl.**

USPC **D29/112**

(58) **Field of Classification Search**

USPC D29/100, 102, 105, 106, 108, 112, 122; D14/205, 223; D2/870, 878, 891

(57)

CLAIM

The ornamental design for earmuffs, as shown and described.

DESCRIPTION

FIG. 1 is a front perspective view of earmuffs showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

1 Claim, 7 Drawing Sheets
